UNITED STATES PATENT OFFICE.

GREEN R. STARNES, OF CHARLOTTE, NORTH CAROLINA, ASSIGNOR OF ONE-HALF TO SAMUEL T. STOWE, OF CHARLOTTE, NORTH CAROLINA.

PORABLE CAMP.

No. 926,683.

Specification of Letters Patent. Patented June 29, 1909.

Application filed February 29, 1908. Serial No. 418,612.

To all whom it may concern:

Be it known that I, GREEN R. STARNES, a citizen of the United States, residing at Charlotte, in the county of Mecklenburg and State 5 of North Carolina, have invented a new and useful Portable Camp, of which the following is a specification.

This invention relates to portable camps and is particularly designed for use by convicts, surveying parties, and other gangs of 10 men working at remote points where proper sleeping accommodations cannot be had.

The object of the invention is to provide a sectional house each of the sections being 15 mounted on its own running gear and designed to be drawn from place to place in the same manner as an ordinary wagon.

Another object is to provide sections which in themselves do not constitute complete 20 structures but which when assembled will form a complete house the size of which will be dependent upon the number of portable sections utilized.

Another object is to provide a portable 25 sectional house which is provided with all necessary sanitary arrangements.

A further object is to provide sections which can be securely fastened together and the roofs of which are designed to lap so as 30 to prevent leaking between the sections.

With these and other objects in view the invention consists of certain novel features of construction and combinations of parts 35 which will be hereinafter more fully described and pointed out in the claims.

In the accompanying drawings is shown the preferred form of the invention.

In said drawings: Figure 1 is a horizontal section through a sectional house embodying 40 the present improvements. Fig. 2 is a view partly in front elevation and partly in section of the complete house. Fig. 3 is a side elevation of one of the sections. Fig. 4 is a transverse section through the removable 45 pan. Fig. 5 is a detail view of the adjoining ends of the two sections of the holding rod which is employed where the invention is used for housing convicts.

In the drawings the house has been shown 50 made up of four sections A, B, C and D respectively and it is of course to be understood that if desired the section A may be eliminated or any desired number of sections C can be employed. Each section is mounted 55 upon running gear 1 of the usual or any pre-

ferred construction, the same having any suitable means for harnessing draft animals thereto so that the sections can be drawn from place to place.

In Fig. 3 the section B has been shown in side elevation. This section can, if desired, constitute one end of the sectional house or if preferred, and as shown in the drawings, it can constitute the end portion of one room of a two-room house. Inasmuch as the general construction of all of the sections is practically the same it is thought that the side elevation of this one section is sufficient to disclose the construction of the remaining sections. Each section has a front wall 2 and a rear wall 3 and sections A, B, and D are also provided with one side wall 4, 5, and 6 respectively. Upstanding corner posts 7 are arranged at opposite ends of the end walls 2 and 3 and a suitable roof 8 is arranged upon each section, said roof being preferably formed of corrugated metal having one side portion extending beyond the corresponding side of the house section as indicated at 9 so that when the various sections are assembled 20 in the manner hereinafter set forth these roof sections will lap as indicated in Fig. 2 and thus prevent leakage at the joints.

The sections are preferably provided along their open sides with hanging partitions 10 constituting supports for ceilings 11 which are below and spaced from the roof and which, with the floors and walls of the sections, are preferably sheathed with metal so as to prevent the escape of persons from the 30 building should the device be in use by convicts. As indicated in Fig. 3 the sections are also provided with depending flanges 12 located along the longitudinal side of the floors, these flanges being provided with bolt 35 openings 13. Truss rods 14 are also arranged longitudinally under the sections. As indicated in Fig. 1 the walls 4 and 5 of the sections A and B are preferably located at the right sides of said sections while the 40 wall 6 of section D is located at the left side of said section. Section C is open at both sides but otherwise is of the same construction as the sections A, B and D. Section A may be provided with any suitable arrangement of doors and windows and the sections 45 B, C and D may also be provided with suitable arrangements of doors and windows. The doors and windows of these sections B, 50 C and D, however, are preferably provided 55

with gratings so that there will be no danger of the occupants of said sections escaping therefrom should the device be used as quarters for convicts. The sections B, C and D 5 are provided with two rows of bunks 15, the foot boards 16 of which are spaced from the end walls of the sections and the bunks within the sections B and D are also spaced from the walls 5 and 6, thus forming aisles or passageways 17. The bunks extend directly to the open sides of these sections as indicated in Fig. 1.

When it is desired to assemble the sections herein described the same are moved into 15 the relative positions shown in the drawings so that the corner posts will come into contact. These posts are provided with bolt holes 18 which register and the bolts 19 are insertible through these holes and utilized 20 for binding the sections together. Bolts are also inserted through the openings. When the parts are thus assembled the open side of section A is closed by the wall 5 of section B and the two walls 5 and 6 together with the 25 end walls 2 and 3 of sections B, C and D form a large room adjoining the section A and with which it communicates through a door 20 located within the wall 5. In view of the fact that the bunks are arranged in the manner hereinbefore described it will be apparent 30 that when the sections are assembled these bunks will form a continuous series surrounded by the aisles or passageways 17 as shown in Fig. 1.

35 In order that suitable means may be provided to which the shackles may be fastened each section is provided adjacent the foot board of its bunks with a holding rod 21 having crank arms 22 which are pivotally connected to the floor and are so proportioned that when they are swung in one direction the rods 21 will assume positions above the foot portions of the bunks and where the shackles can be readily attached to them. 40 The rods 21 within section B have extensions 23 fastened to operating levers 24 which are fulcrumed upon the wall 5 and are provided with suitable locking means. The rods within the section B are also provided with 45 angular heads 25 which project beyond the open side of the section and are designed to extend into corresponding sockets 26 in the ends of rods 27 mounted within the section C. These rods 27 also have angular heads 50 similar to the heads 25 for projecting into sockets in rods 28 pivotally supported within the section D. By providing these heads and sockets the rods of the various sections 55 can be coupled together and all operated by 60 the levers 24 so as to swing into or out of operative positions.

One or more of the sections are provided at one end with guide cleats 29 supporting a pan 30 which is preferably formed of zinc or 65 other material which will not readily corrode

and which is designed to be drawn outward from under the section and removed therefrom. Each of these pans is located below a stool such as indicated at 31 and is designed to receive deposits therefrom. It will thus 70 be seen that the house can be preserved in a sanitary condition for the reason that the pans can be removed and cleaned as often as desired.

The section A is particularly designed for 75 use as officers' quarters but it is to be understood that if desired this section may be eliminated whereupon the walls 5 and 6 will constitute the sides of the house. Any suitable heating apparatus may be provided. 80 For example, one or more stoves may be placed within the two rooms. Although only one section, C, has been shown it is to be understood that any desired number of these sections may be utilized in connection with 85 the sections B and D so that a room of any desired proportions can be produced. When it is desired to remove the house to another location it is merely necessary to detach the bolts 19 from the corner posts 7 and flanges 12 whereupon said sections can be drawn in 90 the same manner as ordinary wagons.

What is claimed is:

1. A portable house comprising separate 95 wheel-supported sections, each having one side wall and one open side, a wheel-supported section insertible between the first mentioned sections and having two open sides, said sections, when assembled, constituting 100 a structure having a single continuous compartment, means for detachably securing the sections together, a shackle-engaging rod movably mounted within each section, means for coupling the rods of the sections together 105 to prevent independent movement thereof, and means in one of the sections for simultaneously elevating the coupled rods.

2. A portable house comprising separate 110 wheel supported sections each having one side wall and one open side, a wheel supported section insertible between the first mentioned sections and having two open sides, said sections when assembled constituting a structure having a single continuous compartment, means for detachably securing the 115 sections together, a bunk within each section, a shackle engaging rod movably mounted within each section and shiftable into position above the bunk therein, means for coupling the rods of the sections together to 120 prevent independent movement thereof, and means in one of the sections for actuating the coupled rods.

In testimony that I claim the foregoing as 125 my own, I have hereto affixed my signature in the presence of two witnesses.

GREEN R. STARNES.
